ASH COLLECTOR FOR UNDERFEED
STOKERS

Haskell C. Carter, Portland, Oreg., assignor to
Iron Fireman Manufacturing Company, Port-
land, Oreg.

Application November 25, 1932, Serial No. 644,314

7 Claims. (CL. 110—165)

This invention relates generally to underfeed stokers, and particularly to means for collecting and removing ashes therefrom and the depositing of same in conveniently placed ash cans.

The main object of this invention is the construction of an ash remover which will require the addition of a minimum number of parts in order to make this feature available on any standard type of underfeed stoker.

The second object is to produce an efficient form of ash remover which will be exceedingly durable in its construction and which will have its working parts easily accessible for inspection and maintenance.

These, and other objects, will become more apparent from the specification following as illustrated in the accompanying drawings, in which:

Fig. 1 is a side elevation of the stoker.

Fig. 2 is a plan of Fig. 1 showing portions of the fuel feed and ash removal ducts broken away.

Fig. 3 is a section taken along the line 3—3 in Fig. 1.

Fig. 4 is a section taken along the line 4—4 in Fig. 2.

Fig. 5 is a section taken along the line 5—5 in Fig. 2.

Fig. 6 is a section taken along the line 6—6 in Fig. 1.

Fig. 7 is a front elevation of the device.

Similar numbers of reference refer to similar parts throughout the several views.

Referring in detail to the drawings, there is shown a circular retort 10 above which is mounted a tuyère section 11 having an outwardly extending rim 12 which is spaced from the inside of the furnace lining 13 which in turn rests on the furnace floor 14. On the floor 14 is erected a base 15 upon which rests the floor 16 of the plenum chamber 17 upon whose side walls 18 rests the flanged bottom 19 of the retort 10. The lower portion 20 of the retort section is preferably turned to rotatably receive the ash collector ring 21 which is held down by means of the studs 22 which project from the retort 10.

The ring 21 has a downturned rim 23 whose lower edge is provided with teeth 24 which can mesh with the flight 25 of the inclined ash removal worm 26 which is confined within the ash duct 27 whose lowermost end 28 projects into the space between the plenum chamber wall 18 and an inner side of the lining 13. The upper side of the end 28 is cut away to expose the worm 26. The lowermost end of the worm 26 is supported

by the duct end 29. Projecting upwardly from the rim 23 are the vertical slicer bars 30 whose upper ends travel around the rim 12.

Coal is fed into the retort 10 through the fuel feed duct 31 by means of a fuel feed screw 32. The duct 31 connects with the housing 33 which forms the lower part of a hopper unit, the details of which are explained in my copending application, Serial Number 644,316 filed November 25, 1932 and now Patent No. 1,974,133 is issued September 18, 1934. In this instance however, it is desirable to pass the ash removal duct 27 through the hopper 34, thereby forming a support for the duct 27 as well as permitting a more desirable alignment thereof.

The worm 26 is driven by means of a sprocket 35 which rests against the bearing 36, preferably supplied with a grease seal 37. A shear pin 38 secures the sprocket 35 to the worm 26 whose end 39 is squared to facilitate the insertion of a new pin 38 should same become sheared due to an abnormal load on the ash removal worm 26. A chain 40 passes around the sprocket 35 and around a sprocket 41 on the sloping shaft 42 which is substantially parallel with the axis of the ash removal worm 26. The shaft 42 is connected by means of a universal joint 43 to a power take-off 44 which derives its power from the transmission contained within the housing 45, which transmission is driven from a motor 46 through a belt 47. A fan for supplying air to the plenum chamber 17 is contained within the casing 48. The sprockets 35 and 41 are contained within a casing 49 which is provided with a removable cover 50. The sprocket 41 is secured to the shaft 42 by means of a shear pin 51.

The operation of the device is as follows: Assuming that coal is being fed upwardly into the retort 10 and gradually consumed and that any clinkers projecting beyond the rim 12 are broken off by the passing of the slicer bars 30, it will be seen that the broken clinkers together with the fine particles will find their way through the openings 52 between the spokes 53 whose upper edges 54 constitute the top side of the ring 21. The ashes 55 are permitted to fill the space around the walls 18, as shown in Fig. 5, although some of them, of course, fall directly into the ash removal duct 27 and are carried away by the worm 26. Others are carried around by the rotating ring 21 into the duct 27, from whence they find their way through the two-way chute 56 into the ash cans 57 through their roof-shaped covers 58. By the use of two cans 57 a greater storage

capacity for the ashes is provided and the removal thereof is also facilitated.

While it would seem desirable to provide a cut-off for the ends of the chute 56 to prevent the escape of ashes therefrom while the cans 57 are being emptied, in practice this is not found necessary owing to the extremely slow manner in which these ashes emerge from the stoker.

It can be seen from the foregoing that by the addition of a relatively small number of parts to the ordinary type of stoker, a very satisfactory and inexpensive form of ash remover is made available.

I claim:

- 15 1. In an underfeed stoker including a circular retort, in combination, a toothed ash ring rotatably mounted around said retort below the upper edge thereof, a trough-shaped ash removal duct mounted in an inclined position with its lower end under said toothed ring, an ash removal worm occupying said duct and engaging a tooth of said ring, the upper end of said ash duct being fully enclosed and terminating in a chute, a driving sprocket for said worm located at the upper end of said duct, and means for rotating said sprocket.
- 20 2. In an underfeed stoker having a retort, an ash conveyor comprising a toothed ring rotatably mounted under the outer edge of the retort, a conveyor duct having an open end under said ring, and having a worm within said duct, the worm flight meshing with the teeth in said ring, and means for rotating said worm from the end thereof which is opposite its ring-engaging end.
- 25 3. A stoker having a circular retort provided with a rotatable ash ring mounted under the outer edge of the retort, an inclined ash duct having its lower end terminating under said ring, a helical ash removal worm within said duct,

said ring having teeth thereon which engage the helix of said worm, the lower end of said duct having the upper portion thereof cut away to permit said worm to engage said teeth and also to permit ashes falling from said retort to enter said duct, and means for driving said worm.

4. In a stoker having a circular retort, the combination of a rotatable toothed ash conveyor ring mounted under the outer edge of the retort, an inclined ash conveyor duct sloping upwardly from a point below said toothed ring, the portion of said duct under said ring having its top side open to receive ashes conveyed by said ring, an ash removal worm in said duct engaging said toothed ring for the purpose of driving same, a prime mover, and driving connections between said prime mover and the uppermost end of the worm adapted to deliver power thereto.

5. The combination of claim 4, and a plurality of upright slicer bars carried by said toothed ring and having their upper ends disposed around the outer edge of said retort.

6. In an underfeed stoker having a retort, an ash conveyor comprising a ring rotatably mounted under the outer edge of the retort, said ring having downwardly projecting teeth, an ash conveyor duct having an opening under said ring, and a worm within said duct meshing with the teeth of said ring.

7. In an underfeed stoker having a circular retort: an ash leveling device mounted to travel around said retort below the upper edge thereof, said device having teeth, combined conveyor and elevator comprising an inclined ash removal duct mounted with its lower end under said device, an ash removal worm in said duct having a flight operatively engaging the teeth of said device whereby to drive the device, and means for rotating the worm.

HASKELL C. CARTER. 40
